UNITED STATES PATENT OFFICE

1,990,030

BATH MITTEN

Samuel S. Jaffe, New York, N. Y.

Application June 9, 1934, Serial No. 729,859

2 Claims. (Cl. 15—227)

This invention relates to bath mittens.

The object of the invention is to provide a mitten having an outer covering made of mesh fabric woven from strong or substantially non-stretching thread for frictionally engaging the skin in order to loosen and remove foreign matter therefrom.

Another object of the invention is to provide a construction which will create considerable friction between the mitten and the skin so as to render it especially useful with shower baths as the frictional heat generated will offset the effect of the chill imparted by the water.

A further object of the invention is to provide a glove which may be rinsed or washed while on the hand to remove the cleansing agent therefrom after its application to the skin, so as to avoid the necessity of removing the glove for rinsing or washing.

A further object of the invention is to provide a mitten which will fit both the right and left hand.

A still further object of the invention is to provide a mitten having a coarse outer material for frictionally engaging the skin and a soft lining for working up a lather.

Other objects of the invention will appear as the disclosure progresses. The drawing is intended to merely indicate a possible embodiment of the invention. It is obvious that the actual needs of manufacture may necessitate certain mechanical changes. It is therefore not intended to limit the invention to the embodiment illustrated but rather to define such limits in the appended claims.

In the drawing

Figure 1 is a front view of the mitten.

Figure 2 is a longitudinal section thereof.

Figure 3 is a section on line 3—3 of Figure 1.

Referring now to the drawing in detail, the mitten is shown as having a large portion 1 to receive the fingers and a thumb portion 2. Both of these portions form the body of the mitten which is made of open mesh fabric woven from strong, substantially non-stretching thread. Within the body is a lining 3 made of soft material such as canton flannel or flannelette. The lining extends to the finger and thumb portions and terminates substantially opposite the wrist of the wearer as at 4 where it is sewed to the open mesh fabric by the stitches 5. The inner lining is slightly gathered so that a space 6 is formed between said lining and outer fabric to hold a lather and to allow the lining to slightly wrinkle so as to provide a some-

what abrasive surface on which to quickly form a lather.

Both sides of the body portion of the mitten are alike or of the same material so that the mitten will serve for the right or left hand thus making it necessary to use one mitten.

In the operation the cake of soap 7 is placed in the palm of the hand as shown in Figure 2 and a lather 8 worked up by moving the soap against the soft fleecy lining 3. The lather will then fill the space 6 and pass out through the open mesh fabric of the body of the mitten to be applied to the skin.

The fabric forming the body of the mitten provides means to readily retain the cleansing agent by reason of the fact that the fabric is of open mesh and of substantially non-stretching thread. The strong and non-stretching threads engage the skin and frictionally and positively grip and cleanse the skin without injury or harmful effects. Also, the strong non-yielding threads when rubbed against the skin create considerable friction so as to warm the body, which renders the mitten invaluable in connection with a shower bath as the frictional heat produced will offset the effect of the chill imparted by the water.

The flesh cleansing and massaging article which is herein shown in the form of a mitten, affords a massaging action which could not be obtained if the outer covering were formed of soft material. While the threads of the net will not abrade or scratch the skin, they serve to impart thereto the desired massaging glow when the article is used after the bath, and these threads serve when the article is used as a washing or cleansing utensil to most effectively remove foreign substances from the skin. One of the particular reasons why this construction is so effective is that the outer covering is of a reticulated material having sufficiently open mesh so as to permit of minute projections or portions of the flesh into the interstices whereby rubbing action imparted to the article under pressure will serve to cause the threads surrounding the minute flesh-projecting portions to grip and massage the skin.

A most particular advantage in having a two ply article of different material, is that the inner lining of soft material will work up a lather and retain the lather like a sponge until the lather is used up by the outer covering. Another advantage of the doubled wall construction is that the space between the walls fills up with the lather and acts as a reservoir until the lather is absorbed by the outer covering.

Having described my invention, I claim

1. A mitten of the class described composed of outer and inner layers of fabric, the outer layer made of open mesh fabric woven from a strong non-stretching thread and the inner layer made of soft fleecy material.

2. A mitten of the class described composed of outer and inner layers of fabric, the outer layer made of open mesh fabric woven from a strong

non-stretching thread and the inner layer made of soft fleecy material, said inner layer terminating substantially at the wrist of the wearer, the edges only of the inner layer being marginally secured to the outer layer, and the body of the inner layer being gathered so that a space is left between the inner and outer layer to hold soap lather.

SAMUEL S. JAFFE.
